226,521

COMBINED BOTTLE AND CLOSURE THEREFOR

Nathan B. Lerner, Chicago, Ill., assignor to W. Braun
Company, Chicago, Ill.

Filed Oct. 20, 1971, Ser. No. 191,153

Term of patent 7 years

Int. Cl. D9—01

U.S. Cl. D9—118

FIG. 1 is an elevational view of a combined bottle and closure therefor showing my new design;

FIG. 2 is a top plan view;

FIG. 3 is an exploded elevational view looking from the right of FIG. 1;

FIG. 4 is a perspective view;

FIG. 5 is a cross-sectional view taken on line 5—5 of FIG. 4, and

FIG. 6 is a bottom plan view.

I claim:

The ornamental design for a combined bottle and closure therefor, as shown.
